Attest.

UNITED STATES PATENT OFFICE.

VIKTOR REMBOLD, OF KIEL, GERMANY.

COMPRESSOR.

Application filed November 29, 1921. Serial No. 518,640.

To all whom it may concern:

Be it known that I, VIKTOR REMBOLD, a German citizen, residing at Kiel, in the German Republic, have invented a new and useful Improvement in Compressors, of which the following is a specification.

This invention relates to air compressors and to installations connected therewith wherein alternately high or low pressure is required such for instance as for motor boats. Installations of this kind according to present day practice, have generally a high and a low pressure compressor, each separately driven by its own motive power. In similar installations, however, both compressors may be coupled together in such a manner as to be operated by a single engine, but in such case one of the compressors either moves without doing useful work or it has to be stopped during the work of the other compressor and part of the engine work is wasted. Again, it is possible to provide a single high pressure compressor which shall also serve for low pressure, in which case, also, there is loss in useful work.

According to this invention, arrangement is made to increase the volume of air to be compressed in the transition from high pressure to low pressure working periods, and this is preferably attained by the provision of an additional compressing space or chamber which affords an increased volume of air for compression within such limits as to maintain unaltered the engine power required for operating the compressor at high pressure of compression.

According to the accompanying drawing, the compressor consists of four cylinder spaces I, II, III and IV. The suction valves of these spaces are designated with the reference characters s_1 , s_2 , s_3 and s_4 respectively; in like manner the characters d_1 , d_2 , d_3 and d_4 represent the delivery valves and K_1 , K_2 , K_3 and K_4 the coolers. Furthermore the valves N_1 , N_2 , M_1 , M_2 , M_3 and M_4 represent in a diagrammatic way the switching organs which serve for the connection of the pressure stages for high and low pressure operation. D designates a three-way valve, by means of which the suction valve s_4 may be brought in connection either with the strainer a_2 or with the conduit c .

If the compressor shall work as high pressure compressor, the valves N_1 and N_2 are opened and the three-way valve D is brought

into the position shown in the drawing, while the valves M_1 , M_2 , M_3 and M_4 will remain in closed condition. The air which is sucked in through the strainer a_1 will then enter through the suction valve s_1 into the space I (first stage of compression) and leave this space through the delivery valve d_1 , thereupon flow through the conduit b , the cooler K_3 , the conduit c and after passing through the three-way valve D and the suction valve s_4 will come into the cylinder space IV. From this space the air will discharge through the delivery valve d_4 and thereupon enter into the cylinder space II through conduit f , cooler K_4 , conduits h and o and suction valve s_2 . The air will thereupon leave the cylinder space II through the delivery valve d_2 in order to enter into the cylinder space III (last pressure stage) through conduit e , cooler K_2 , conduit g and suction valve s_3 . The high pressure air will discharge through the delivery valve d_3 , conduit p and cooler K_1 in order to be conveyed to its place of consumption. As can be seen all four pressure stages are passed one after the other by the air.

In order to operate the compressor as low-pressure compressor, the valves M_1 , M_2 , M_3 , and M_4 are opened, while the valves N_1 and N_2 are being closed. The three-way valve D must be brought into such a position by rotating the same by 90 degrees that the suction valve s_4 will be in connection with the strainer a_2 . The course of the flow of the air will thus be as follows: The outer air enters through the strainer a_1 and the suction valve s_1 into the cylinder space I, leaves the same through the delivery valve d_1 and flows through conduit i , cooler K_2 , conduit g and suction valve s_3 into the cylinder space III. From the latter the air will discharge through the delivery valve d_3 in order to flow through conduit p and cooler N into the collecting pipe r . At the same time air is being sucked in by the strainer a_2 and pass through suction valve s_4 into the cylinder space IV, from which it will flow into the cylinder space II through delivery valve d_4 , cooler K_1 , conduits h and o and suction valve s_2 . The pressure air will discharge from the cylinder space II through delivery valve d_2 and flow through conduits e and l and cooler N also into the collecting pipe r . In case of low-pressure operation, therefore, two stages of compression viz I

and III as well as IV and II are connected in series and the two currents of the compressed air will be joined with each other in the conduit r . Since the valve M_1 is opened, at this place an equalization of the two air-currents can take place between the two parallel flows of pressure air after having passed the first pressure stages.

I claim:—

- 10 1. A compressor comprising a plurality of compression cylinders, coolers associated with said cylinders, and a conduit system comprising means for connecting said cylinders through said coolers in a series arrangement of pressure stages commencing with a low pressure air inlet and terminating in a high pressure delivery pipe and means for alternatively connecting said cylinders through said coolers in a parallel arrangement of a less number of stages commencing in a plurality of low pressure air inlets and terminating in a single delivery pipe substantially as and for the purpose set forth.
- 15 2. A compressor comprising a plurality of compression cylinders, coolers associated therewith, and a conduit system comprising means for connecting said cylinders through said coolers in a series arrangement of pressure stages commencing with a low pressure air inlet and terminating in a high pressure delivery pipe and means for alternatively connecting said cylinders through said coolers in a parallel arrangement of a less number of stages commencing in a plurality of low pressure air inlets and terminating in a single delivery pipe substantially as and for the purpose set forth.

VIKTOR REMBOLD.
